(21) Appl. No.: **29/364,891**

CLAIM

(22) Filed: **Jun. 30, 2010**

The ornamental design for a charging stand for instruments for testing the authenticity of diamonds and moissanite, as shown and described.

(51) **LOC (9) CL. 13-02**

DESCRIPTION

(52) **U.S. Cl. D13/108**

(58) **Field of Classification Search** D13/107-110,
D13/118-119, 184, 199; D14/251, 253,
D14/432, 434; 320/107-115

FIG. 1 is a top perspective view showing our new design for a charging stand for instruments for testing the authenticity of diamonds and moissanite;

See application file for complete search history.

FIG. 2 is a front elevation view;
